UNITED STATES PATENT OFFICE.

ALBERT WEBER, OF PROVIDENCE, RHODE ISLAND.

FASTENING MEMBER FOR VANITY CASES.

Application filed October 15, 1926. Serial No. 141,747.

My invention relates to a fastening device for vanity cases comprising a plurality of hinged sections, one of which carries an entrant member adapted to cooperate with a receiving plate or other member provided with a clasp opening and carried by the other of said sections.

The essential objects of my invention are the facility of manipulation; security of the interengaged parts; the avoidance of projecting hooks or latches, as well as rendering unnecessary the cutting or recessing of the peripheral walls of the sections; and inexpensiveness of construction.

My invention consists in providing in the receiving plate of one section a hole bounded by resilient tongues and normally of such restricted dimensions that an entrant member in the other section must in passing through the hole flex the tongues.

Further invention consists in means for pushing the head of the entrant member through the hole from locked position against the resistance of the tongues.

Invention also consists in further combinations falling within the scope of certain of the appended claims.

In the accompanying drawings which form a part of this specification

Figure 1 is a front elevation of a vanity case in open position containing my invention,

Figure 2, an enlarged partial section of the same on line 2-2 of Figure 1,

Figure 3, a fragmentary front elevation of the socket portion of the case, and

Figure 4, a like elevation of the same showing a portion of the housing flange broken away.

Like reference characters indicate like parts throughout the views.

As herein shown 7 and 8 represent in a general manner two sections of a vanity case connected by a hinge 9. One section, 7,

which for convenience is styled the body section, comprises a back 11 and peripheral flange 12; while the companion section, 8, which may be styled the cover section, comprises a back 13, and flange 14. A receiving

plate or housing flange 16 upon the flange 12 consists in this instance of a transversely U shaped annular member having an outer side or portion 17 integral with, attached to, or frictionally engaging the flange 12, an

inner side or portion 18, and a top portion 19. The side 18 forms in conjunction with

the back 11 a circular cavity 20 adapted to receive a cosmetic compact 21 of any usual construction. The top 19 of the flange is provided, diametrically opposite the hinge 7, with a hole 23, preferably elliptical, from diametrically opposite portions of which extend radial slots 24 opening into intermediate portions of curved slots 25 disposed transversely to the first slots. The hole and slots form two opposed resilient tongues 27 having centrally positioned cavities 28 in their margins constituting curved bifurcations. The hole, slots, and tongues constitute receiving and retaining means for an entrant member hereinafter to be described.

Means for dislodging such entrant member consists of a resilient flat bar 29 having its ends slidable in slots 30 in the side 17. Fixed to the middle of the bar is a rod or plunger 32 passing loosely through perforations 33 and 34 in the side 17 and flange 12 respectively. Integral with or fixed to an intermediate portion of the plunger parallel with the bar 29 is a plate 36 provided with a cam face 37 in its upper edge. The hole 23 is in transverse alignment with the plunger 32.

Referring to the section 8 a retaining ring or flange 38 in this instance holds in engagement with the back 13 a mirror 39, and has upon its exposed face, at a point diametrically opposite the hinge, an entrant member 40 comprising a neck portion 41 and a curved head portion 42. The latter portion 42 is somewhat greater in diameter than the narrowest portion of the hole 23 formed by the cavities 28 through which it passes when the sections are closed. This passage is permitted by reason of the yielding character of the tongues 27 whose four corners only are in the path of the advancing head 42, as indicated in Figure 3 wherein the broken lines represent the circumference of the head 42 relatively to the tongue corners. After this passage the tongues snap back to their original plane behind the head and prevent escape of the latter. The described passage is effected by pinching together the wings 7 and 8.

To dislodge the entrant member the parts may be grasped and manually pulled apart with sufficient force to cause the head 42 to pass back through the hole 28 against the resistance of the tongues which after passage again resume their normal plane.

To manually pull or pry apart the sec-

tions is sometimes awkward or difficult, and for this reason the push pin or plunger mechanism is afforded. The cam face 37 contacts with the rounded lower portion of the head 42 when the latter is engaged by the clasping means. Hence by pushing the plunger 32 inwardly the cam face pushes the entrant member above the tongues, in a path at right angles to the path of the plunger.

I claim:

1. In a fastening member for a vanity case, two sections hingedly connected, an entrant member carried by one section, a housing flange carried by the other section and provided with a hole in the path of the entrant member and of less breadth than the entrant member, said flange being provided also with slots extending from the sides of the hole and with slots communicating with the first slots and disposed transversely thereto.
2. In a fastening member for a vanity case, two hingedly connected sections comprising backs and sides, an entrant member carried by the back of one section, a housing flange upon the side of the other section provided with a hole to permit passage of the entrant member, and resilient tongues integral with the flange around the opening and provided with cavities forming the opening, the portions of the tongues adja-

cent the cavities being interposed in the path of the entrant member.

3. In a fastening member for a vanity case, two hingedly connected sections, an entrant member comprising a neck supported by one section and a head, a housing flange carried by the other section, and oppositely disposed resilient tongues integral with the flange in the path of the entrant member provided in the center of their adjacent ends with cavities adapted to permit passage of the head therewith in contact with the tongues.

4. In a fastening member for a vanity case, two hingedly connected sections comprising backs and sides, an entrant member comprising a neck supported by one section and a head thereon, a housing flange upon the side of the other section provided with a hole of less breadth than the head in the path of the entrant member, and with slots radiating from the hole permitting passage of the head through the hole, a plunger yieldingly mounted in the side of the second section between the flange and the back of the second section and a cam plate upon the plunger engageable with the lower portion of the head.

In testimony whereof I have affixed my signature.

ALBERT WEBER.
